US00D956688S

(12) **United States Design Patent** (10) **Patent No.:** **US D956,688 S**
(45) **Date of Patent:** **** Jul. 5, 2022**

(54) **CHARGING DOCK**

(71) Applicant: **JUUL Labs, Inc.**, San Francisco, CA (US)

(72) Inventors: **Claire O'Malley**, San Francisco, CA (US); **Brandon Cheung**, San Francisco, CA (US)

(73) Assignee: **JUUL Labs, Inc.**, San Francisco, CA (US)

(**) Term: **15 Years**

(21) Appl. No.: **29/673,942**

(22) Filed: **Dec. 18, 2018**

Related U.S. Application Data

(63) Continuation of application No. 29/654,823, filed on Jun. 27, 2018, now Pat. No. Des. 887,975.

(51) **LOC (13) Cl.** **13-02**

(52) **U.S. Cl.**

USPC **D13/108**; D27/194

(57) **CLAIM**

The ornamental design for a charging dock, as shown and described.

DESCRIPTION

FIG. 1 is a top, front, and right side perspective view of a charging dock of our design;

FIG. 2 is a top view thereof;

FIG. 3 is a bottom view thereof;

FIG. 4 is a right side view thereof;

FIG. 5 is a left side view thereof;

FIG. 6 is a rear view thereof; and,

FIG. 7 is a front view thereof.

The broken lines illustrate portions of the charging dock that form no part of the claimed design.

1 Claim, 6 Drawing Sheets
